UNITED STATES PATENT OFFICE

NELS B. ANDERSON, OF BELLINGHAM, WASHINGTON

DOUBLE CAN-SEAMER HEAD

Application filed November 10, 1930. Serial No. 494,491.

My invention relates to improvements in double can-seamer heads and has for an object to provide a can bottom and top seamer head having two pairs of seaming rollers with the individual rollers of each pair independently actuated to bear diametrically opposite each other on the can.

Another object of my improvement is to provide said two pairs of rollers disposed to bear on the can at right angles with each other.

Another object of my improvement is to adapt the mechanism to oscillate one of said pair of rollers through longer arcs than the said other pair.

Another object of my improvement is to provide to oscillate said pairs of rollers at nonsimultaneous periods.

Another object of my improvement is to provide relatively large bearing surfaces to resist the rolling pressures.

Another object of my improvement is to provide adjustments to accommodate cans of different diameters.

Another object of my improvement is to provide separate minute adjustments to exactly position each roller.

Another object of my improvement is to dispose operative parts of the head of similar shapes and dimensions opposite each other through the axis of revolution to provide balanced running at high speeds.

Other objects of my improvement will appear as the description proceeds.

I attain these and other objects of my improvement with the mechanism illustrated in the accompanying three sheets of drawings, forming a part of this specification, in which Figure 1 is a front elevation of the gearing of my seamer head down to the broken line $a-a$, Fig. 2 is a front elevation of the seamer head proper from the broken line $a-a$, Fig. 3 is a bottom plan view of Fig. 2, Fig. 4 is a plan section of Fig. 2 on the line 4-4, Fig. 5 is a plan section of Fig. 2 on the line 5-5, Fig. 6 is a front elevation of a segregated rocker shaft arm, Fig. 7 is a bottom plan view of Fig. 6, Fig. 8 is a longitudinal view of a rocker arm stud and pin, Fig. 9 is an end ele-

vation of Fig. 8 and Fig. 10 is a side elevation of a roller pin.

My invention is suited for seaming bottoms on can bodies and also for seaming tops on filled cans. A complete machine, of which my invention is a part, also includes mechanism for carrying can bodies with bottoms in place thereon, or filled cans with tops in place thereon, to an elevator which moves them one at a time to and from the chuck shown on the lower end of the mechanism herewith illustrated. Therefore, this invention concerns itself with said other mechanism of the complete machine only to provide means for joining the two parts in operative relation.

Similar characters refer to similar parts throughout. Certain parts are broken away to show other parts hidden thereby.

With more particular reference to the designated parts: Bracket base 11 is assumed to be suited for fastening to the frame of said complete machine at a place provided to dispose the mechanism illustrated herewith in operative relation with the said other parts of the machine not herein illustrated.

On the upper end of base 11 is bracket 12 having mounting boss 17 thereon. Next below bracket 12 is bracket 13 fastened to base 11 with bearing boss 18 thereon and extended at 14 which has bearing boss 19 on its outer end. Fastened to the lower end of base 11 is bracket 15 with bearing boss 20 thereon and extended therefrom is arm 16 with bearing boss 21 on the outer end thereof. The axes of bearings 18 and 20 coincide with the axis of mounting annular boss 17 and the axes of bearings 19 and 21 coincide and are parallel with the said axis of boss 17.

Chuck shaft 22 has its upper end mounted and fastened in annular boss 17 and is extended downward through the entire mechanism to mount chuck 24 on its lower end to be stationary therewith. Hollow eccentric shaft 23 is mounted for revolution on chuck shaft 22. Upper, head-frame disc 25 is mounted for revolution on eccentric shaft 23 and has hub shaft 26 integral therewith extended upward therefrom mounted on eccentric shaft 23 and in bearing boss 20 for revolution.

Countershaft 27 is mounted for revolution in bearing bosses 19 and 21 and has set ring 28 fastened thereon above bearing 19 disposed to bear thereon and support said countershaft in operative position.

Driving gear wheel 29 is fastened on the upper end of countershaft 27 for engagement with mechanism connected to a prime mover not shown. Gear wheel 30 is fastened on countershaft 27 below bearing 19 to engage with gear wheel 34 which is fastened on hollow eccentric shaft 23 to drive the same. Gear wheel 31 is fastened near the lower end of countershaft 27 to engage with gear wheel 32 which is fastened on the upper end of hub shaft 26 to drive the same. Set ring 33 is fastened on the upper end of hub shaft 26, disposed to bear on the upper end of the hub of gear 32, the lower end of which bears on the upper end of bearing boss 20, to support the hub shaft in operative position.

The construction provides that driving countershaft 27 through gear wheel 31 drives upper, head-frame disc 25 and through gear wheel 30 drives eccentric shaft 23. Gear wheels 31 and 32 preferably are of the same diameters, but preferably gear wheel 30 is of larger diameter than gear wheel 34 in order that eccentric shaft 23 may revolve at a higher rate than upper, head-frame disc 25 for reasons to be explained later.

Lower, head-frame disc 35 is mounted for revolution near and on the lower end of eccentric shaft 23 and is fastened to and parallel with upper head-frame disc 25 by frame rods 36, 36, 36, 36, which are fastened to lower head-frame disc 35 and extended through holes in upper head-frame disc 25 smaller than the bodies of the rods to cause shoulders on the same to bear against the lower side of the upper head-frame disc which is clamped thereagainst by nuts 37 engaged on the protruding threaded ends of the said rods. Upper head-frame disc 25 and lower head-frame disc 35 fastened together by frame rods 36 constitute the head frame of the machine.

The space on eccentric shaft 23 between discs 25 and 35 is occupied by four eccentrics, which, beginning next to upper head-frame disc 25, are designated as 38, 39, 40 and 41 respectively. These eccentrics are mounted on the cam shaft and fastened thereto to revolve therewith, and are circular discs mounted eccentrically on the shaft. Preferably, they are all of the same diameter and are associated in two pairs. Pair of eccentrics 38, 39 are of equal eccentricity and oppositely disposed relatively on the line $b-b$. Pair of eccentrics 40, 41 are of equal eccentricity, but of greater eccentricity than are eccentrics 38, 39, and are oppositely disposed relatively on the line $c-c$. The head preferably revolves in a forward direction, as indicated by the arrow in Fig. 3, and line $c-c$

is preferably about 20° in advance of line $b-b$. As illustrated, line $b-b$ is in the horizon.

On each of said eccentrics is mounted an eccentric strap with an arm attached. On eccentric 38 is strap 42 with arm 43, on eccentric 39 is strap 44 with arm 45, on eccentric 40 is strap 46 with arm 47 and on eccentric 41 is strap 48 with arm 49 thereon.

As illustrated, arms 43 and 45 of eccentric straps 42 and 44 respectively on pair of eccentrics 38, 39 are disposed on opposite sides of the pair of eccentrics with their center lines coinciding with line $b-b$ of said pair of eccentrics. But arms 47 and 49 of eccentric straps 46 and 48 respectively, one pair of eccentrics 40, 41 are on opposite sides of said pair of eccentrics and their coinciding center lines are at right angles with strap arms 43, 45, although the center line $c-c$ of their pair of eccentrics is shown as 70° backward in rotation from said center line of said arms. This feature will be more fully explained.

Rocker shaft 51 is mounted for oscillation in head upper and lower head frame discs 25 and 35 and has a roller arm 67 on the lower end thereof beneath bottom head-frame disc 35 and set ring $a51$ on the upper end thereof to bear on the top side of upper head-frame disk 25 and retain the rocker shaft in operative position. Rocker shaft 51 is disposed adjacent and, in rotation, forward of the outer end of eccentric strap arm 43.

Rocker shaft 53 is mounted for oscillation in head discs 25 and 35 adjacent and forward of, in rotation, the outer end of eccentric strap arm 45, has a roller arm 67 on the lower end thereof beneath bottom head-frame disc 35 and set ring $a53$ on the upper end thereof to bear on the top of upper head-frame disc 25 and retain said rocker shaft in operative position.

Rocker shaft 50 is mounted for oscillation in head upper and lower head-frame discs 25 and 35 adjacent of and, in rotation, forward of the upper end of eccentric strap arm 49 and has a roller arm 64 on its lower end beneath lower head-frame disc 35 and a set ring, $a50$, on its upper end to bear on top of upper head-frame disc 25 to retain the rocker shaft in operative position.

Rocker shaft 52 is mounted for oscillation in upper and lower head-frame discs 25 and 35 adjacent of and, in rotation, forward of the end of eccentric strap arm 47 and it has a roller arm 64 on its lower end beneath lower head-frame disc 35 and a set ring similar to $a53$, on its upper end to bear on top of disc 25 to retain the rocker shaft in operative position.

Operative connection between the eccentric strap arms 43, 45, 47, 49 and the rocker shafts 51, 53, 52, 50 is made by rocker arms 63, 63, 54, 54 respectively. Rocker arms 63 and 62 are entirely similar as are rocker arms 54 and 129

54. Also rocker arms 54 and 63 are similar except, for reasons of compactness of the head, they are relatively right and left hand.

One of rocker arms 54 is chosen for particular segregated illustration in Figs. 6-9. The main body of the rocker arm 54 has transverse hole 55 therethrough through which the rocker shaft may be extended and fastened by a clamping screw through bifurcated body ends $a54, b54$, also the position of the arm on the shaft is preferably localized by a key $b52$ as shown. Similar keys $b50, b51, b53$ are shown in shafts 50, 51 and 53 respectively. Near the end of the arm not bifurcated is guide-way notch 57 in one side of the body only and transverse to hole 55. Provision is made to fasten plate 58 on the arm over one end of guideway notch 57, and in the outer edge of this plate midway of the guideway is supporting-screw notch $a58$. Slot 56 is made in the wall of the arm through the bottom of guideway notch 57. Rectangular block 60 is adapted to slide in guideway 57 and has stud bolt 61 on one end thereof with a threaded end $b61$ thereon and also has wrist pin 62 on the end opposite said stud. A tapped hole $a60$ is made in one side of block 60. The several parts of the rocker arm are assembled by extending stud 61 through slot 56 and clamping block 60 in slideway 57 by a nut $a61$ on the threaded end of the stud bearing on the arm body, fastening plate 58 in place after supporting screw 59 is engaged in hole $a60$ in the block and notch $a58$ in the edge of the plate is engaged in the neck of the supporting screw. Block 60 may be adjusted in guideway 57 by screw 59 when it may be securely held in place by clamping nut $a61$. Thus assembled, rocker shaft 50 is extended through hole 55 of the rocker arm which is localized in rotation on the shaft by a key and longitudinally by clamping screw $c54$ through bifurcated ends $a54, b54$. Before clamping the arm by screw $c54$ pin 62 is engaged in the hole in the end of eccentric strap arm 49.

In the same manner the other rocker arm 54 is mounted on rocker shaft 52 and the pin 62 thereon is engaged with the hole in the end of eccentric strap arm 47.

50 Also rocker arms 63, 63 are mounted on rocker shaft 51 and 53, respectively, and pins 62 thereon are engaged with eccentric strap arms 43 and 45 respectively. Thus studs 61 may be adjusted in slots 56 to lengthen or 55 shorten the eccentric strap arms considerably and finer adjustments of said arm lengths is made possible by the use of supporting screws 59 to retain the studs in desired positions in the slots while clamping nuts $a61$ are applied.

As stated, rocker shafts 50, 52 have roller arms 64, 64 fastened on the lower ends thereof disposed adjacent and beneath lower head-frame disc 35, while rocker shafts 51, 53 have 55 roller arms 67, 67 fastened on the lower ends

thereof adjacent and beneath lower head-frame disc 35. Each of said roller arms is alike and they are differently designated in pairs to correspond with the two pairs of eccentrics 38, 39 and 40, 41.

70 On roller arms 67, 67 are mounted for revolution on pins 66 therein rollers 68, 68, and on roller arms 64, 64 are mounted for revolution on pins 66 therein rollers 65, 65. One of similar pins 66 is shown segregated in Fig. 10. These pins consist of body 66 and thin broad head $a66$ and said body is extended through a hole near the bifurcated ends of the arms, shown at $a67, b67$ and $a64, b64$. With the pins in place in the arms they are 80 retained therein by clamping screws $c67$ and $c64$ though holes in said bifurcated ends. The pins are set in the arms disposed to provide space for the rollers on the pins between heads $a66$ thereof and said arms.

85 Rollers 68, 68 are similar to rollers 65, 65 except that grooves $b68$ in rollers 68 are shaped to be adapted for the number one or first operation rollers while grooves $b65$ in rollers 65 are shaped to be adapted for the 90 number two or second operation rollers. Rollers 68, 68 have flanges $a68$ and rollers 65, 65 have flanges $a65$. All of the rollers are disposed to cause said roller flanges to be closely adjacent and above flange $a24$ of 95 chuck 24. And the grooves of all of the rollers are in the plane of chuck flange $a24$ and closely approach said chuck flange when in their rolling or closed positions shown in dotted lines at $68', 68'$ and $65', 65'$, while 100 they are separated from said flange a space sufficient to allow the rolled edge of a can bottom or top to intervene when in their open position shown in full lines at $68, 68$ and $65, 65$.

105 It may be seen that the rocker shafts serve as fulcrums between the eccentric strap arms and the can rollers, thus it requires outward movement of the strap arms to produce centerward movement of the can rollers and vice versa.

110 Now consider the relative movement between the eccentrics and their straps. The eccentrics are fastened on eccentric shaft 23 and revolve therewith, and the straps are engaged by wrist pins 62 which revolve with upper and lower head discs 25, 35. Upper head-frame disc 25 is integral with its hub shaft 26. Hub shaft 26 is connected to driving countershaft 27 by equal gears 31, 32 and 115 is revolved at the rate of shaft 27. Eccentric shaft 23 is connected to shaft 27 by gears 34, 30 which are preferably in the ratio of 10 to 11. So that eccentric shaft 23 makes 11 revolutions while hub shaft 26 makes 10 revolutions, and upper and lower head-frame discs 25, 35 make ten revolutions while eccentrics 38, 39, 40 and 41 make eleven revolutions; that is, the eccentrics gain one complete revolution during each ten turns of the discs. 120 125 130

Then we may assume, while studying the related movements of the operative parts of the head, that wrist pins 62 are stationary while the eccentrics make one revolution. Figs. 4 and 5 may be consulted. The eccentrics cause the straps to oscillate on wrist pins 62, thus having no effect on the pins when lines *b*—*b* and *c*—*c* of the eccentrics are at right angles with the strap arms and including arcs of about 30° on each side of said right-angle locations. During the remaining parts of the revolution the eccentrics are effective in moving wrist pins 62 in oscillations on rocker shafts 50, 51, 52 and 53. As illustrated, the can rollers stand in outward position to allow a can to be removed from or placed on the chuck by the elevator, not shown.

Revolve the eccentrics forward 180° and strap arms 43, 45 will cause number one rollers 68, 68 which perform the first part of the seaming operation to bear on the edge of any can end on chuck 24, but strap arms 47, 49 yet hold number two rollers 65, 65 outward. Continue the revolution forward of the eccentrics for 70° when arms 47, 49 will be fully extended to cause number two rollers 65, 65 which perform the last part of the seaming operation to bear on said can edge on the chuck flange, and the number one rollers will have but recently ceased to bear on the can. Continuing the forward revolution of the eccentrics and the number two rollers will leave their bearing positions directly and rapidly open till by the time another 45° in revolution has been passed they will be open together with the number one rollers and the can may be removed by said conveyor and another can placed on the chuck by the same. Thus there will be an arc of about 65° to be traversed by the eccentrics during which the positions of the rollers will allow cans to be placed on and removed from the stationary chuck 24.

During the period of one revolution of the eccentrics above examined, which, in fact, was taken from eleven revolutions thereof, head discs 25, 35 have made ten complete revolutions and the small arcs which were noted as the periods during which the rollers were bearing on the cans to attain the seaming thereof were in fact each several complete revolutions of the roller arms while the rollers were bearing with great pressure on the can edge as it lay on the periphery of flange *a*24 of the chuck.

It is now clear that by placing action line *c*—*c* of pair of eccentrics 40, 41 only 20° in lead of action line *b*—*b* of pair of eccentrics 38, 39 rather than 90° in lead thereof, as are strap arms 47, 49 in lead of strap arms 43, 45, a sufficient lead is provided between the seaming operation of the number one and number two rollers and, what is very important

in a high-speed seamer, a relatively large arc of revolution remains during which cans may be removed from and placed on the chuck.

It is also clear that the operating forces released within the seamer head are largely equally balanced against each other thus providing a self-contained resistant mechanism well suited for rapid and excellent work and long service.

Having thus disclosed my invention, what I claim as new therein and desire to secure by Letters Patent is,—

1. A double can-seamer head including a head frame mounted for revolution, a stationary chuck disc disposed concentric with the axis of revolution of said head frame, four circular-disc eccentrics mounted eccentric to said head frame axis for revolution on said head frame axis, four seaming rollers each mounted for revolution on an axis central thereto and also mounted for oscillation on said head frame in the plane of said chuck disc, four eccentric straps, one mounted for revolution on each of said eccentrics also mounted on mechanical connections with said head frame for reciprocative oscillation, said mechanical connections from each of said eccentric straps to each of said rollers causing said rollers in pairs simultaneously to oscillate and bear on any can on said chuck, simultaneously to withdraw from said can also alternately to bear in close succession on said can and simultaneously to withdraw therefrom, means to revolve said eccentrics, and means to revolve said head frame.

2. A double can-seamer head including a vertical stationary chuck shaft, a hollow eccentric shaft mounted for revolution on the chuck shaft, a seamer head frame mounted for revolution on the eccentric shaft, means to mount the eccentric shaft and the seamer head frame in bearings for revolution, two pairs of eccentrics fastened on the eccentric shaft for revolution therewith within the seamer head frame, the eccentrics of each pair of said two pairs of eccentrics being disposed side by side in substantially opposite relation and the said pairs of eccentrics disposed side by side in diagonal relation with each other, an eccentric strap mounted on each eccentric, an eccentric strap arm integral with each eccentric strap the arms of each pair of said eccentric straps being in a line and substantially opposite each other, the said pairs of eccentric strap arms being substantially at right angles with each other, four rocker shafts mounted for oscillation in the head frame being disposed equidistant from and parallel with the chuck shaft and being equally spaced therearound, a rocker arm fastened to each rocker shaft, a wrist pin adjustably fastened in each rocker arm engaged with one of the eccentric strap arms, a roller arm fastened on each rocker shaft, a roller mounted for revolution on each of

100

the roller arms one opposite pair of rollers having first-operation seaming grooves in the peripheries thereof and the other opposite pair of rollers having second operation seaming grooves in the peripheries thereof, all of said seaming grooves being disposed in the same plane, a chuck disc fastened on the lower end of the chuck shaft having a peripheral flange thereon in the plane of the roller grooves, means to revolve the head frame, and means to revolve the eccentric shaft in the same direction with the head frame and more rapidly.

3. The rocker arm assembly of the seamer roller movement of a double can-seamer head, including an arm body having a rocker shaft hole therethrough and having a guideway notch in one side thereof at right angles to said rocker shaft hole and also having a bolt slot therethrough entering said notch parallel with said shaft hole, a bolt having a threaded end and a wrist pin end with an intervening square body having a tapped hole in one side thereof, said threaded bolt end being extended through said bolt slot and being retained therein by a nut on the bolt, said square bolt body engaging said notch and said wrist pin end protruding from said arm body parallel with said rocker shaft hole therein, a plate fastened on one side of the arm body over one end of the guideway notch having a notch in one edge thereof aligned with said tapped hole in the square bolt body, and a supporting set screw engaged in said plate notch and in said tapped hole in the bolt.
